JESSIE B. MEADE, OF WORDEN, ILLINOIS.

METAL INNER CASING FOR AUTOMOBILE TIRES.

1,371,180.

Specification of Letters Patent.

Patented Mar. 8, 1921.

Application filed May 21, 1920. Serial No. 383,178.

To all whom it may concern:

Be it known that I, JESSIE B. MEADE, a citizen of the United States, residing at Worden, in the county of Madison and State 5 of Illinois, have invented new and useful Improvements in Metal Inner Casings for Automobile-Tires, of which the following is a specification.

The object of my present invention is the 10 provision of a simple and inexpensive internal tire armor that is susceptible of being quickly and easily fabricated and is of such flexible character as not to interfere with the resiliency and the cushioning capacity 15 of the tire.

To the attainment of the foregoing the invention consists in the improvement as hereinafter described and definitely claimed.

In the accompanying drawings, hereby 20 made a part hereof:—

Figure 1 is a transverse section showing my novel armor as properly positioned between a tire casing and a liner.

Fig. 2 is a plan view showing a portion 25 of the casing removed to display the armor.

Fig. 3 is a detail in large section showing connected units compressed in the armor.

Fig. 4 is a detail perspective illustrative 30 of the manner of interlocking the units of the armor.

Similar numerals of reference designate corresponding parts in all of the views of the drawings.

In Fig. 1 I illustrate a wheel rim 1, a 35 tire casing 2, and a protective liner 3 for an inner tube, all of which may be and preferably are of the ordinary well known construction.

In accordance with my invention I inter- 40 pose between the liner 3 and the tread portion of the casing 2 an armor such as illustrated in Figs. 1 and 2, the said armor being flexible in all directions and being substantially imperforate and therefore calculated 45 to effectively protect an inner tube without detracting in serious measure from the resiliency of the tire.

My invention resides in the construction 50 of the armor *per se*, and in accordance with my invention the armor is composed of a plurality of rectilinear units 4. The said units 4 are made of an appropriate metal or alloy in the form of plates, and each plate is slightly concavo-convex in conformity 55 with the curvature of the tire, the units or plates 4 are arranged in three series around

the tire, the units or plates of the side series being provided with hooks 5 at their inner ends, and each unit of the longitudinal central series is provided with a hook 6 and 60 with three apertures 7, 8 and 9; the said apertures being of rectilinear configuration, and the end apertures 7 and 8 being connected with one edge of the unit or plate by channels 10 while the aperture 9 is connected 65 with one end of the unit or plate by a channel 11 which, by preference intersects one of the channels 10 as shown in Fig. 4.

By reason of the construction described it will be readily apparent that the units 4 of 70 the two side series may be expeditiously and easily connected to the units 4 of the longitudinal central series; it being simply necessary as a condition precedent to the interlocking of the units to position the hook 75 5 of one side unit as shown in Fig. 4, and slip the said hook through one channel 10 and on one end of the longitudinal central unit until the hook is co-incident with the adjacent aperture 7 in the longitudinal central unit whereupon the side unit will be 80 free to swing or flex on the longitudinal central unit. To connect the units 4 of the longitudinal central series together it is simply necessary to slip the hook 6 of one unit 85 endwise through the channel 11 of an adjoining unit until said hook 6 is co-incident with the aperture 9 of said adjoining unit whereupon the hook 6 may be rocked into engagement with and flexibly connected to 90 the outer wall of the aperture 9 which wall is rounded somewhat in cross section as illustrated.

It will be apparent from the foregoing 95 that an armor constructed in accordance with my invention may be quickly and easily fabricated of a collection of the units 4, and that when interposed between the casing 2 and the liner 3 the said armor will be possessed of a high degree of flexibility in all 100 directions and being also practically imperforate will effectively prevent puncture or blow-outs of the inner tube of the tire without appreciably robbing the tire of its springiness.

Having described my invention, what I 105 claim and desire to secure by Letters-Patent is:—

A flexible imperforate metallic armor for use in a tire, comprising a longitudinal central series of flexibly connected plate-like units, each of said units being rectangular

and concavo-convex in form and provided on one side edge with a curvilinear hook and being provided adjacent to its other side edge and its ends with rectangular apertures and 5 being further provided in its inner side with channels each of which extends from an aperture to the margin of the unit, and two side series of units each of which is rectangular and concavo-convex in form and each

of which is provided at its inner end with 10 a curvilinear hook; the hooks of the longitudinal central units being disposed in the side apertures of adjoining units, and the hooks of the side series of units being disposed in the end apertures of the longitudinal 15 central units.

In testimony whereof I affix my signature.
JESSIE B. MEADE.
